CLAIM

The ornamental design for a tool roll, as shown and described.

DESCRIPTION

FIG. 1 is a perspective view of the tool roll showing the new design;

FIG. 2 is a top view of the tool roll;

FIG. 3 is a bottom view of the tool roll;

FIG. 4 is a left side view of the tool roll;

FIG. 5 is a right side view of the tool roll;

FIG. 6 is a rear view of the tool roll; and,

FIG. 7 is a front view of the tool roll.

The short broken lines illustrate portions of the tool roll that form no part of the claimed design. The long broken lines depict stitching that forms no part of the claimed design.

1 Claim, 5 Drawing Sheets
